UNITED STATES PATENT OFFICE

107,473

DESIGN FOR A PIANO

William Zaiser, Rockville Centre, N. Y., assignor
to The Rudolph Wurlitzer Company, De Kalb,
Ill., a corporation of Ohio

Application June 19, 1937, Serial No. 69,921

Term of patent 3½ years

To all whom it may concern:

Be it known that I, William Zaiser, a citizen of the United States, residing in Rockville Centre, county of Nassau, and State of New York, have invented a new, original, and ornamental Design for a Piano, of which the following is a specification, reference being had to the accompanying drawing forming a part thereof.

In the drawing:

Figure 1 is a perspective view of a piano embodying my new design, and showing the cover in open position.

Figure 2 is a front elevation of a piano embodying my new design but showing the cover closed.

Figure 3 is an end elevation of the same.
Figure 4 is a top plan view of the piano with the cover closed.

The dominant features of the design reside in the contrasting band extending at the level of the keyboard across the front and around the end panels, the vertically ribbed panel extending from the pedals to the keyboard, and the music rack as shown.

I claim:

The ornamental design for a piano substantially as shown.

WILLIAM ZAISER.
